UNITED STATES PATENT OFFICE.

EDWARD L. HOPKINS, OF COLUMBUS, OHIO, ASSIGNOR TO THE JEFFREY MANUFACTURING COMPANY, A CORPORATION OF OHIO.

ANCHOR-JACK.

1,240,210.

Specification of Letters Patent. Patented Sept. 18, 1917.

Application filed August 31, 1911, Serial No. 646,986. Renewed January 10, 1913. Serial No. 741,350.

To all whom it may concern:

Be it known that I, EDWARD L. HOPKINS, a citizen of the United States, residing at Columbus, in the county of Franklin and State of Ohio, have invented certain new and useful Improvements in Anchor-Jacks, of which the following is a specification, reference being had therein to the accompanying drawing.

10 This invention relates to improvements in anchor jacks and in particular to a type adapted to be expanded within a mine tunnel, or between the ceiling and floor of a chamber, and provides a rigid anchor for 15 the end of a mining machine feed cable. A particular advantage of this construction is the fact that the end of the feed rope is anchored to the shoe independent of the extensible upright or the pivoting bolts and 20 yet the line of tension passes directly through the pivot point.

Previous to this an end of a cable was attached to the upright post near its point of pivot or to the bolt upon which the upright post and the shoe are pivoted. Obviously when the cable is attached to the post above the pivot point there is considerable tendency for the post to bend and when attached to the pivot bolt induces a shearing stress to which this member should not be subjected. A particular advantage of the present construction is that both of these objectionable features are eliminated and the end of the cable is attached to the 35 shoe independently of the upright and the pivot bolt therefor. Preferably, it is attached to an upright fin cast integrally with the shoe and so located that the line of tension passes through the pivot point, 40 thereby giving the desired wedging effect to the two members without subjecting the post to bending stresses or the bolt to shear.

Referring to the drawings;

Figure 1 is a side elevation of the anchor jack with the central portion of the upright post cut away;

Fig. 2 is an end elevation of the lower portion of the anchor jack;

Fig. 3 is a perspective view of the forked lower extremity of the upright post; and

Fig. 4 is a perspective view of the shoe.

In the drawings, the numeral 1 represents a flat rectangular shoe upon the upper surface of which are formed at its outer edges 55 two upright lugs 2. A forked end piece 3

is fastened to the lower end of the tubular upright post 4, the prongs 5 of the end piece 3 being spread to a sufficient width to fit within the upstanding lugs 2. Bolt holes 6 are formed in the lower ends of the prongs 60 5 to register with the bolt holes 7 in the upper ends of the upstanding lugs 2. Shoulders 8 are provided on the outer faces of the prongs 5 and are adapted to bear against the upper ends of the lugs 2. The holes 6 and 7 65 in the lugs and prongs are made sufficiently large as compared to the size of the bolts or rivets which pass through them, so that the shoulders will bear down against the tops of the lugs and receive all the downward 70 pressure instead of subjecting the bolts 9 to shear.

A rotatable collar 10 is mounted on the upper end of the post 4 and is provided with outward extending handles 11 by 75 which the collar is rotated, thereby extending the threaded rod 12. This means for extending the upright member may be of any suitable form, the one illustrated being a well known type.

An upright fin 13 is formed integrally with the base of the shoe 1 and located half-way between the two lugs 2. A hook-shaped nose 14 is formed on its upper end, the center of the cut-out portion being located directly in line with the hole 7 of the lugs. The hook is so shaped that an eye or a loop on an end of a feed cable 15 attached to a mining machine may be slipped over its end and when pulled upon will bring the line of tension directly through the pivot point between the shoe and the upright. The location of the tension member may vary through a considerable angle in a vertical plane and still pass through this pivot 95 point.

It will be observed that the line of tension not only passes approximately through the axis of the pivot, but also that the point of cable attachment is approximately in the 100 vertical plane of the pivotal axis. In other words, the point of cable attachment is approximately in the axis of the pivot. This arrangement insures that the line of tension shall pass approximately through the pivot 105 point not only when the cable is horizontal, as shown, but also when it is inclined upward or downward. It will be seen that if the cable were to be inclined upward away from the shoe, and if the point of attach- 110

ment were positioned otherwise than as shown, there would be a tendency for the cable to lift up and bend the part of the shoe to which it might be attached. With 5 my construction the thrust through the upright 4 serves to hold down that part of the shoe to which the cable is attached.

It will, of course, be understood that while a single hook is shown, the invention 10 in its broader aspects is not limited to this construction, and that other means for attaching the cable may be used.

Another important feature of this construction is that the tension is transmitted 15 directly to the shoe by means of fin 13. This, in conjunction with the shoulders 8 of the fork of the upright, renders it possible to subject the jack to severe strains without causing injury to the pivotal connection 20 between the upright and the shoe. This result is of importance as, to insure proper working of the jack, the upright should be in condition to turn easily on its pivots so as to align properly and accurately 25 with the shoe. Obviously, any injury to the pivots 9 would prevent this, and it is the main object of this invention to avoid such injury by providing a jack so constructed as to relieve the pivotal connection between 30 the upright and the shoe of all strains and stresses due to the heavy work to which jacks of this character are subjected.

While I have referred to the use of this anchor as particularly adapted for anchoring 35 the end of a mining machine feed cable, it is obvious that it may be used in a great variety of ways where it is desired to anchor the end of a tension member between two walls or supports between which the jack 40 may be expanded.

What I claim is:

1. In an anchor jack, a shoe, and an upright horizontally pivoted to the shoe, the shoe having means adapted to be connected 45 with a cable and to receive the tension thereof at a point approximately in the vertical plane of the axis of the said pivot, said means being independent of the pivotal connection between the shoe and the upright.

50 2. In an anchor jack, a shoe, an upright horizontally pivoted to the shoe, a fin carried by the shoe and adapted to be attached to a cable end and having its point of cable

engagement approximately at the point of intersection of the pivotal axis and the 55 longitudinal axis of the said upright.

3. In an anchor jack, the combination of a shoe, an upright, a forked end piece carried by said upright and pivotally connected to the shoe, the said end piece being provided with 60 lateral shoulders in engagement with the shoe in all operative positions of the upright, and means for attaching a cable to said shoe, said means being independent 65 of the pivotal connection between the forked end piece and the shoe.

4. In an anchor jack, the combination of a shoe provided with integral lugs having bolt holes and laterally projecting shoulders concentric with said holes, an upright, a 70 forked end piece secured to said upright and loosely pivoted to said lugs, said end piece being provided on its prongs with shoulders in engagement with the aforementioned shoulders of the said lugs to transmit to 75 the latter the thrust of the upright, and means for attaching a cable to the shoe independently of the pivotal connection between the upright and the shoe.

5. In an anchor jack, a shoe, upright extending lugs at each side of the shoe, an upright post, a forked extension on the lower end of the post, the two prongs of said fork being pivoted to the lugs of the shoe, a central fin formed on the shoe, and 85 a hook at the upper end of the fin adapted to be engaged by a tension member, the hook being so located that the line of tension passes through the pivot point.

6. In an anchor jack, a shoe, upright extending lugs at each side of the shoe, an upright post, a forked extension on the lower end of the post, the two prongs of said fork being pivoted to the lugs of the shoe, a central fin formed on the shoe, and means 95 on the upper end of the fin for attaching a tension member thereto, the tension member engaging fin being so located that the line of tension passes through the pivot point.

In testimony whereof I affix my signature 100 in presence of two witnesses.

EDWARD L. HOPKINS.
